UNITED STATES PATENT OFFICE.

AUGUST C. SPAHN, OF EVANSVILLE, INDIANA, ASSIGNOR TO BERNARDIN BOTTLE CAP COMPANY, OF EVANSVILLE, INDIANA, A CORPORATION OF INDIANA.

FRICITION CAP FOR CONTAINERS.

Application filed August 16, 1928. Serial No. 299,947.

The invention relates to caps for closing jars and other containers, and which are adapted to be held frictionally thereon.

One object of the invention is to provide 5 an improved cap of this type in which the skirt is provided with a substantially continuous annular bead to grip the side wall of the container and spaced arcuate gripping surfaces to supplement the gripping of the 10 continuous gripping surface and cause the caps to be held securely on the container, notwithstanding irregularities or slight variations in form.

Another object of the invention is to provide 15 a cap in which a sealing disk for engaging the top rim of the container is loosely held in the cap so that it will not puff or buckle when it is subjected to heat or moisture and which will be retained in connected 20 relation to the cap preliminary to the application of the latter to the container so that they need not be separately placed on the container in the sealing operation.

Other objects of the invention will appear 25 from the detailed description.

The invention consists in the several novel features hereinafter set forth and more particularly defined by the claims at the conclusion hereof.

30 In the drawings Fig. 1 is an inverted plan of a cap embodying the invention. Fig. 2 is a section on line 2-2 of Fig. 1. Fig. 3 is a section on line 3-3 of Fig. 1, showing the cap applied to a glass container. Fig. 4 is a 35 sectional perspective of the cap. Fig. 5 is a section on line 5-5 of Fig. 3. Fig. 6 is a diagrammatic view illustrating the deflection of the flange of the cap before and after it is applied to the container.

40 The invention is exemplified in a cap comprising a top-wall 7, which is adapted to extend over the mouth of the container and an annular skirt 8 depending from and integrally formed with the top. The cap is 45 formed of suitable sheet metal so that the skirt will be sufficiently resilient to adapt it to fit around and conform to the container. The skirt comprises a cylindrical portion 10 immediately below the top, a por-

tion immediately below the portion 10 which has an annular groove struck on a rather small radius, to form an annular substantially continuous inwardly projecting bead 9, and a slightly flared portion 11 below the bead 9. The lower edge of the skirt is re- 51 vverted as at 12 to avoid a raw edge and to stiffen its lower end. The lower portion 11 of the skirt is indented or inset to form 55 separated elongated arcuate surfaces 13 which are generally V-shaped in vertical 60 section to grip the container below the annular bead. The indented gripping portions 13 are normally positioned inwardly of the 65 vertical plane of the inner periphery of the annular bead 9 as indicated by dotted lines in Fig. 6 so that when the cap is applied to a rigid container a , these portions will be forced outwardly to insure the gripping of 70 the container notwithstanding irregularities or slight variations in the diameters of the 75 container. The portions of the skirt between the arcuate gripping portions 13 are preferably slightly greater in circumferential length than said portions and this leaves 80 the portions of the skirt between the gripping portions 13 free to contract or flatten, as shown in Fig. 5, when the latter are expanded by the container so that the portions 85 13 will be put under tension. The arcuate gripping portions 13 will flex outwardly 80 without tending to separate the annular bead from the container. The contraction of the skirt portions between the arcuate portions 13 tends to constrict the portions 85 of the bead 9 above them and as a result the arcuate supplemental gripping surfaces will not tend to destroy the gripping effect of the annular bead. This construction adapts the cap for effectively gripping containers, notwithstanding the inevitable commercial variations in glass containers. In instances when the caps are used for hot packs it is necessary to make provision for the escape of pressure in the container during the application of the cap to the container. For this 95 purpose the bead 9 is interrupted at 9 a , to provide a vent.

In practice it has been found that when

disks are interposed between the top of the cap and the mouth of the bottle, to prevent the contents of the container from contacting with the metal top of the cap, and to form 5 a top seal, and are frictionally held therein, they must fit so tightly in the cap that they will bulge from heat or moisture because the margin of the disk is confined by the cap. This sometimes results in causing leakage 10 of the contents of the container around the disk. To overcome this possibility the invention provides a sealing disk which is loosely fitted in the cap so that there is ample room for its expansion. An objection to the 15 use of a loose disk, however, is that it increases the work in applying the cap when it is separately applied to the container. For this purpose the sealing disk 14 is loose 20 in the cap so as to leave a slight marginal space around it or so that its diameter is less than that of the skirt portion 10 but greater than that of the inner periphery of the bead 9. When the disk is forced into the 25 cap beyond the bead it will be retained in connected relation to the cap so that no separate handling of the disk is necessary in sealing the container.

The invention exemplifies a cap, the skirt of which is provided with an inwardly projecting bead to grip the side wall of the container and with supplemental arcuate gripping portions below the bead; also a cap in which a sealing disk is loosely fitted to permit its expansion and is held in connected 35 relation to the cap.

The invention is not to be understood as restricted to the details set forth, since these may be modified within the scope of the appended claims, without departing from 40 the spirit and scope of the invention.

Having thus described the invention, what I claim as new and desire to secure by Letters Patent, is:

1. A friction cap for containers, comprising a top adapted to extend over the mouth of the container and an integral annular skirt of resilient material depending from the top and adapted to extend around the side-wall of the container, having an annular 45 inwardly projecting bead with a substantially continuous surface to continuously engage and frictionally grip the side-wall of the container and having a series of indented portions, separated from one another to 50 form supplemental gripping surfaces.

2. A friction cap for containers, comprising a top adapted to extend over the mouth of the container and an integral annular skirt of resilient material depending from 60 the top and adapted to extend around the side wall of the container, having an annular inwardly projecting bead with a substantially continuous surface to continuously engage and frictionally grip the side-wall of 65 the container and having a series of arcuate

indented portions forming supplemental gripping surfaces which are outwardly flexible without expanding the gripping surface on the bead and are spaced apart sufficiently to permit the skirt portions between them to contract. 70

3. A cap for application to containers, comprising a top adapted to extend over the mouth of the container and an annular skirt of resilient material depending from the top and adapted to extend around the side-wall of the container, having adjacent the top an annular substantially continuous inwardly projecting bead having a surface formed to continuously and frictionally grip the side-wall of the container and having a series of indented portions below the bead, forming supplemental gripping surfaces. 75 80

4. A cap for application to containers, comprising a top adapted to extend over the mouth of the container and an annular skirt of resilient material depending from the top and adapted to extend around the side-wall of the container, having adjacent the top an annular substantially continuous inwardly projecting bead having a surface formed to continuously and frictionally grip the side-wall of the container and having a series of indented portions below the bead, extending 90 95 inwardly of the plane of the inner periphery of the bead and forming supplemental gripping surfaces. 100

5. A friction cap for containers, comprising a top adapted to extend over the mouth of the container and an annular skirt of resilient material depending from the top and adapted to extend around the side-wall of the container, having adjacent the top an annular inwardly projecting substantially continuous bead having a surface to continuously and frictionally grip the side-wall of the container and having a series of arcuate portions below the bead forming supplemental arcuate gripping surfaces, said arcuate gripping surface being of less circumferential length than the skirt-portions between them to permit the skirt portions between them to contract. 105 110

6. A friction cap for containers, comprising a top adapted to extend over the mouth of the container and an annular skirt of resilient material depending from the top and adapted to extend around the side-wall of the container, having adjacent the top an annular inwardly projecting substantially continuous bead, having a surface to continuously and frictionally grip the side-wall of the container and having a series of indented portions below the bead forming supplemental arcuate gripping surfaces, the bead having an interruption to permit the pressure in the container to escape while the cap is being applied to the container. 115 120 125

7. A friction cap for containers, comprising a top to extend over the mouth of the 130

vessel and an integral annular skirt of resilient material adapted to extend around the side-wall of the container and having an annular inwardly projecting bead to grip the container, and a sealing disk fitting loosely within the skirt to permit expansion and contraction thereof without bulging and held

in the skirt by the bead, the bead having an interruption to form a vent while the cap is being applied to the container.

10
